UNITED STATES PATENT OFFICE.

JOHN J. WALKOWE, OF DETROIT, MICHIGAN.

SWAGE OR DOLLY BLOCK.

Application filed January 8, 1922. Serial No. 526,754.

To all whom it may concern:

Be it known that I, JOHN J. WALKOWE, a citizen of the United States, residing at Detroit, in the county of Wayne and State of Michigan, have invented certain new and useful Improvements in Swage or Dolly Blocks, of which the following is a specification.

My invention relates to swage or dolly blocks used for bending or straightening sheet metal articles in general but more particularly for use in connection with automobile work for removing dents and bumps on hoods, radiator casings, fenders, etc.

One object of my invention is to provide such a dolly block combining a considerable number of different shaped sides and edges, in order to make it useful for correcting flat as well as bent surfaces and straight as well as curved edges. The dolly block is intended to be held against one side of the work with the portion thereof that coincides with the shape to which the plate has to be finished, and a hammer is used to apply light blows on the other side of the work.

Another object of the invention is to construct the device in a convenient size so that it may be comfortably held in one hand, while using a hammer with the other hand.

In the accompanying drawing the dolly block is illustrated in approximately full size, and

Figure 1 shows a top plan view thereof; Figure 2 a front elevation of Figure 1; and

Figure 3 a cross section along lines 3—3 of Figure 2;

This block, which is preferably solid and made of hard wood or metal has a flat bottom 10 and one flat side 11 forming right angles with the bottom and a sharp corner therewith as at 12. The top 13 is convex or turtle shaped and joins the flat side 11 with a sharp edge 14, see Figure 3, while at 45 the opposite side and front and rear ends it is curved so as to join the bottom with a sharp edge 15 at the right hand end, see Figure 2, an elliptical curve 16 blending with the bottom and running tangentially therewith at the other end of the block.

The two ends together with the remaining side of the contour, as seen in horizontal projection in Figure 1, is formed of curved and straight lines which terminates

on the left side of the figure with an acute angle 17, and on the right side with an obtuse angle 18 where joining the flat side 11. This contour consists of an arc of fairly large radius commencing at the point 17 and at 19 running tangentially into a smaller curve to point 20, where it forms a straight line to point 21 then turns into a circular arc of smaller radius to 22 and finally terminates with a fairly large arc up to point 18. The side having this compound contour runs into the bottom of the block and forms a sharp edge 24 therewith between points 18 and 20, whereas between 17 and 20 no edge is formed but the side is curved into the bottom as already described. Between points 18 and 22 and for about half an inch up on this end to line 23 in Figure 2 the side is flat between lines 15 and 23.

It will now be evident that the flat side 11 has a sharp edge all around it.

In order to form a 90° edge in a plate, the dolly block should be held in one hand and the edge 12 pressed against the plate where the right angle edge is to be formed, while blows are delivered from a hammer on the other side of the plate until the edge is gradually formed. Similarly if a rounded bead is to be formed in a plate, the rounded edge 16 is held under the plate and, according to whether the curvature in the longitudinal direction should be short or long, the proper portion, as between 19 and 20 or between 17 and 19, is selected to press against the plate, while blows are delivered on the other side thereof.

To take out dents in a plate, if it has a narrow surface, the flat side 11 is pressed against it or if it is a wider surface the bottom side 10 is pressed thereto and blows similarly delivered on the opposite side of the plate. For large dents and bumps on curved surfaces, the top portion 13 of the dolly block is used.

Having thus described the invention what is claimed as new is:

1. A dolly block having a convex top, a flat bottom, and a flat side forming a straight edge therewith, the opposite side and both ends emerging in horizontal projection into a contour composed of one straight and several curved lines.

2. A dolly block having a convex top, a flat bottom, and a flat side forming a straight

edge therewith; the opposite side and both ends merging in horizontal projection into a contour composed of one straight and several curved lines, the angle between said 5 bottom and flat side being 90° .

3. A dolly block having a convex top, a flat bottom, a flat side forming a straight edge therewith and the opposite side running parallel with said flat side, and curved ends 10 merging with said opposite side, the edges of said flat side all being sharp.

4. A dolly block having a convex top, a flat bottom and a flat side forming a straight edge therewith and the opposite side and 15 both ends merging in horizontal projection into a contour composed of one straight and several curved lines, the straight part of said contour being shorter than said flat side and running parallel therewith.

20 5. A dolly block having a convex top, a flat bottom, and a flat side forming a straight edge therewith and the opposite side and both ends merging in horizontal into a contour composed of one straight and several 25 curved lines, the straight part of said contour being shorter than said flat side and running parallel therewith and the curved ends of the contour forming respectively acute and obtuse angles with said flat side,

30 6. A dolly block having a convex top, a flat bottom, a flat side forming a straight edge therewith, the opposite side being straight in horizontal projection, curved ends merging with said straight side, said 35 straight opposite side being shorter than said flat side and running parallel therewith, the curved ends forming respectively acute and obtuse angles with said flat side, and a sharp edge being formed with said 40 bottom along said opposite side and one of

said ends from said obtuse angle to the remote end of said straight opposite side.

7. A dolly block having a convex top, a flat bottom, a flat side forming a straight edge therewith, the opposite side being 45 straight in horizontal projection, curved ends merging with said straight side, said straight opposite side being shorter than said flat side and running parallel therewith, the curved ends forming respectively acute 50 and obtuse angles with said flat side, a sharp edge being formed with said bottom along said opposite side and one of said ends from said obtuse angle to the remote end of said straight opposite side, and the remaining 55 one of said ends being curved to blend smoothly into said top and bottom in perpendicular planes of the latter.

8. A dolly block having a convex top, a flat bottom, a flat side forming a straight 60 edge therewith, the opposite side being straight in horizontal projection, curved ends merging with said straight side, the angle between said bottom and said flat side being 90° , the edges of said flat side all being sharp; said straight opposite side being shorter than said flat side and running parallel therewith and the curved ends forming respectively acute and obtuse angles with said flat side, a sharp edge being formed 65 with said bottom along said opposite side and one of said ends from said obtuse angle to and including said straight opposite side, and the remaining one of said ends being curved to blend smoothly into said top and 70 bottom in perpendicular planes of the latter.

In testimony whereof I affix my signature.

JOHN J. WALKOWE. [L. S.]
